UNITED STATES PATENT OFFICE.

ROBERT B. HOUSLEY, OF INDIANAPOLIS, INDIANA.

WASHOUT-PLUG.

1,346,496.

Specification of Letters Patent. Patented July 13, 1920.

Application filed March 17, 1919. Serial No. 283,115.

To all whom it may concern:

Be it known that I, ROBERT B. HOUSLEY, a citizen of the United States, residing at Indianapolis, in the county of Marion and 5 State of Indiana, have invented a new and useful Washout-Plug, of which the following is a specification.

This invention relates to plugs of the character employed in connection with boilers and the like and an object of the invention is to make a plug which will be 10 leak-proof.

Another object is to provide a construction which will insure against crossing of 15 the threads of the cap and nipple members when the cap is being screwed onto or into the nipple.

Another object is to provide guide means 20 on the nipple and cap which will register with one another when placing the cap in position for screwing on the nipple, so that the cap and nipple will be axially aligned with one another and the threads of the cap will match up properly with the threads of 25 the nipple in order that the cap may be readily screwed into place without injuring the threads of either member by crossing of the threads.

Other objects and advantages will appear 30 in the subjoined detailed description.

The accompanying drawings illustrate the invention:

Figure 1 is a cap-end view of a washout plug made in accordance with the provisions of this invention.

Fig. 2 is a side elevation of Fig. 1.

Fig. 3 is a vertical mid section on line indicated by x^3-x^3 , Fig. 1.

Fig. 4 is a plan section on line indicated 40 by x^4-x^4 , Fig. 3.

Fig. 5 is a vertical mid section analogous to Fig. 3 of a modified form of the invention.

Fig. 6 is a plan section on line indicated 45 by x^5-x^5 , Fig. 5.

The washout plug comprises a nipple 1 and a cap 2, the nipple 1 being provided with screw-threads 3 for threading into the orifice made to receive it in a boiler or other 50 container. The nipple 1 is provided in the end opposite the end having the screw-threads 3 with an annular groove or channel 4, the outer wall 5 of said channel being provided with screw-threads 6 adapted to 55 engage screw-threads 7 on an annular flange 8 of the cap. The inner wall 9 of

the groove 4 is smooth on its outer peripheral face and may be slightly tapered outwardly, if desired, and said wall engages the inner face of the flange 8.

The inner wall 9 extends outward beyond the plane of the outer end of the outer wall 5 so that when the cap is applied to the nipple 1 the flange 8 will first engage the outer end of the inner wall 9 to axially align 65 the cap and nipple with one another before the screw-threads 6, 7 come into engagement with one another.

It is desirable to employ packing between the nipple 1 and cap 2 and said packing is 70 in the form of an annulus 10 formed of any suitable packing material and interposed between the outer end of the wall 2 and the inner face of the cap so that when the cap is screwed up tightly the annulus will be 75 compressed between the nipple and cap to prevent leakage through the joint therebetween.

The cap 2 may be provided with an internal wrench seat 11, as in Fig. 3, or may 80 be provided with an external wrench seat 12, as in Fig. 5, according to the desire of the constructor.

Now referring to the form of the invention shown in Figs. 1, 2 and 3, and more 85 particularly to Fig. 3, the cap 2 is provided with or forms an inwardly extending plug 13, there being thus formed an annular groove 14 between the flange 8 and plug 13, and the inner wall 9 of the nipple being inserted in said groove. The inner face of 90 the wall 9 is adapted to engage the peripheral face of the plug 13, since said plug fits the bore 15 of the nipple, so as to aid in guiding the cap 2 into axial alignment with 95 the nipple 1 when the cap 2 is applied to said nipple, to prevent relative crossing of the screw-threads 6, 7 when the cap is subsequently screwed home.

The plug 13 is at least as long as the flange 100 8 and in Fig. 3 is shown somewhat longer, and therefore the wall 9 and plug 13 will first engage when the cap is being applied to the nipple.

In applying the cap 2 shown in Fig. 5 to 105 the nipple 1, it is clear that the first engagement between the cap and nipple will occur between the flange 8 and inner wall 9 and that, in order to bring the threaded portions 6, 7 close enough together to engage 110 one another, the cap and nipple must first be in axial alignment with one another, since

otherwise the cap would bind on the nipple and not slide thereon sufficiently far to permit of said engagement of the screw-threads. This is the reason for the inner wall 9 being made to extend outward beyond the plane of the outer end of the outer wall 5, and thus the flange 8 and inner wall 9 constitute means to insure alining of the cap and nipple axially when the cap is being assembled in place. These guiding means also occur in the form of the invention shown in Figs. 1 to 3, and additional guiding means are afforded by the inner wall 9 and plug 13 since they come into engagement with one another before the threads 6, 7; and thus, in the form of the invention shown in Figs. 1 to 3, the cap can be axially alined with the nipple possibly even quicker than in the form of the invention shown in Fig. 5.

The invention is not limited to the exact details of construction shown in the drawings and described above but embraces such changes and modifications as may lie within the spirit and scope of the appended claims.

I claim:

1. A washout plug comprising a nipple having an annular groove in one end, the outer wall of the groove being provided with screw-threads and the inner wall of the groove projecting outward beyond the plane of the outer end of the outer wall of the groove, and a cap having a flange provided with screw-threads adapted to engage the screw-threads of the nipple.

2. A washout plug comprising a nipple having an annular groove in one end, the outer wall of the groove being provided with screw-threads and the inner wall of the groove projecting outward beyond the plane of the outer end of the outer wall of the groove, and a cap having a flange provided with screw-threads adapted to engage the screw-threads of the nipple, said cap having a plug adapted to fit in the bore of the nipple.

3. A washout plug comprising a nipple having an annular groove in one end, the outer wall of the groove being provided with screw-threads and the inner wall of the groove projecting outward beyond the plane of the outer end of the outer wall of the groove, and a cap having a flange provided with screw-threads adapted to engage

the screw-threads of the nipple, the cap having a plug to fit the bore of the nipple and the inner face of the flange being adapted to engage the outer face of the inner wall of the groove.

4. A washout plug comprising a nipple having an annular groove in one end, the outer wall of the groove being provided with screw-threads and the inner wall of the groove projecting outward beyond the plane of the outer end of the outer wall of the groove, a cap having a flange provided with screw-threads adapted to engage the screw-threads of the nipple, and a packing annulus interposed between the outer end of the inner wall of the groove and the inner face of the cap.

5. A washout plug comprising a nipple having an annular groove in one end, the outer wall of the groove being provided with screw-threads and the inner wall of the groove projecting outward beyond the plane of the outer end of the outer wall of the groove, a cap having a flange provided with screw-threads adapted to engage the screw-threads of the nipple, said cap having a plug adapted to fit in the bore of the nipple, and a packing annulus surrounding the plug and interposed between the outer end of the inner wall of the groove and the inner face of the cap.

6. A washout plug comprising a nipple having an annular groove in one end, the outer wall of the groove being provided with screw-threads and the inner wall of the groove projecting outward beyond the plane of the outer end of the outer wall of the groove, a cap having a flange provided with screw-threads adapted to engage the screw-threads of the nipple, the cap having a plug to fit the bore of the nipple and the inner face of the flange being adapted to engage the outer face of the inner wall of the groove, and a packing annulus surrounding the plug and interposed between the outer end of the inner wall of the groove and the inner face of the cap.

Signed at Indianapolis, Indiana, this 6th day of March, 1919.

ROBERT B. HOUSLEY.
